CLAIM

The ornamental design for an electrical connector of an ultra-violet lamp bulb, as shown and described.

DESCRIPTION

FIG. 1 is a perspective view of an electrical connector of an ultraviolet lamp bulb showing my new design.

FIG. 2 is a front view thereof.

FIG. 3 is a rear view thereof.

FIG. 4 is a left side view thereof.

FIG. 5 is a right side view thereof.

FIG. 6 is a top view thereof; and,

FIG. 7 is a bottom view thereof.

The broken line portion of the figure drawings is included to show unclaimed subject matter only and forms no part of the claimed design.
